UNITED STATES PATENT OFFICE

DIETRICK J. WERFELMAN, OF NEW YORK, N. Y., ASSIGNOR TO DUBIED MACHINERY COMPANY, OF NEW YORK, N. Y., A CORPORATION OF NEW YORK

YARN-CARRIER-CONTROLLING MEANS FOR KNITTING MACHINES

Application filed October 25, 1929. Serial No. 402,341.

The present invention relates to improvements in straight knitting machines, and more particularly to the yarn carrier controlling mechanism.

With ordinary knitting machines it is possible to knit plated angular or other designs as for instance by the means disclosed in the patent of Werfelman and Strelz No. 1,601,545 of September 28, 1926. Up to the present time however, no practical means has existed whereby it is possible to solidly knit such patterns or designs in the fabric itself automatically. The advantages of such solid knitting are many. For instance, the matrix or body color yarn portion of the fabric on which the plating is made in the known device, is entirely eliminated with the fabric knitted by my new device, thereby firstly saving considerable quantities of the yarn and secondly, permitting the production of a solidly knitted design or pattern whereby either side of the fabric can be used.

An object of my invention is to provide improved and practical means whereby a great variety of designs such as angular designs or other patterns can be solidly knitted into a fabric automatically.

Another object of this invention is to so construct said means that the change from one pattern to another may be affected very readily.

A further object is to provide means whereby the stops which control the yarn carriers will be caused to automatically change their positions relative to themselves and to the yarn carriers to control the strokes of the yarn carriers according to the design carried.

Still another object is to provide a novel stop construction which will provide for a minimum loss of space due to the employment thereof without reducing its effectiveness.

And still another object is to provide a comparatively simple construction which may easily and readily be applied to any existing machine without materially changing the construction of the machine itself.

Yet another object is to provide a comparatively simple mechanism which may be manufactured at low cost.

With the above and other objects in view, my invention consists in the novel construction, combination, and arrangement of elements as will hereinafter be more fully described, shown in the accompanying drawings and defined in the appended claims. 55

In the drawings in which similar reference characters denote corresponding parts:

Fig. 1 is a top plan view of one end of 60 the knitting machine showing the stop operating mechanism of my device;

Fig. 2 is a front elevation view of another portion of the said operating mechanism;

Fig. 3 is a section along line 3—3 of Fig. 65 2 seen in the direction of the arrows;

Fig. 4 is a top plan view of the yarn carrier portion of the machine showing in detail the improved stop mechanism.

Fig. 5 is a section along line 5—5 of Fig. 70 2 seen in the direction of the arrows;

Fig. 6 is a reduced detail of the stop mechanism and showing the connection between the same and the stop operating mechanism; 75

Fig. 6a is a perspective view seen from the rear of Fig. 6 showing the strapping arrangement of the stop mechanism;

Fig. 7 is a section along line 7—7 of Fig. 1 also seen in the direction of the arrows; 80

Fig. 8 is a partial top plan view of the yarn carrier portion of the machine showing in detail a modified form of stop mechanism;

Fig. 9 is a section along line 9—9 of Fig. 8; 85

Fig. 10 is a detail view of the connecting means between the stop mechanism and the stop operating mechanism; and

Figs. 11 and 12 show samples of designs which may be knitted with my attachment. 90

Only so much of the machine proper is shown as will be necessary for a full and clear understanding of my invention.

In the drawings *a* denotes the usual oppositely inclined needle beds in which rows 95 of successively operated independent needles (not shown) are arranged transversely of and at opposite sides of the path of travel of the yarn carriers *b'*, *b²*, *b³*, *b⁴*, *b⁵*. Guided over the rails *a'* of said bed is the usual car- 100

riage *c* (shown only partly) which may be operated in well known manner either by hand or automatically and which is provided with the usual plungers *d'*, *d²*, mounted on the front side thereof, and adapted in well known manner to operate the said yarn carriers. Similar plungers (not shown) are mounted at the rear side of said carriage. The said carriage *c* by means of said hand or automatic drive is given reciprocal motion on rails *a'* over the needle bed *a*, in consequence of which the yarn carriers move to and fro in limited manner to be presently described.

15 Two yarn carrier bars 10 and 10', one in front and one in the rear of the needle bed and arranged parallel to rails *a'* thereof are provided and on these bars the yarn carriers are slidably mounted as by means of frictional engagement or other means. Suitably mounted on each of said yarn carriers and adapted to lie on the top surface of the respective bars 10 and 10' in the path of travel of the plungers *d* is a catch mechanism which 20 said plungers are adapted to engage in order to shift the said carriers. Each of said mechanisms comprises a block 11 which has a rectangular cut-out portion 11', intermediate its ends, and the ends 11² and 11³ thereof are beveled as shown. Each plunger *d* is spring actuated and the operating end thereof normally tends to project below the top surface of said blocks 11. Therefore if the said plunger moves over the said block 25 the said end thereof will ride over the beveled ends 11² and 11³ of the block and when it reaches the cut-out portion 11' will slide therein and by abutting against an edge of said cut-out portion will carry the said yarn carrier with it until it is released from the 30 said cut-out portion by the stop mechanism.

The number of yarn carriers employed depends upon the designs which are to be knitted into the fabric, there being a separate carrier for each portion of the design.

35 To limit the extreme left hand position of the yarn carrier *b'* (Fig. 4) the stop block 12 may be employed. Now then this stop block is adjustably mounted on the rail and is provided also with bevelled ends 12' and 12² which lie in the path of travel of said plunger *d'*, whereby as the plunger carrying the stop block 11 of the said yarn carrier rides up onto one end 12² it releases the said block 11 and may continue its motion without the same.

40 The motion of yarn carrier *b²* is controlled by similar stop blocks 13 and 14 mounted to the rear of the bar 10 and which lie in the path of plunger *d²*. Now then to limit the right hand motion of the carrier *b'* it would ordinarily be necessary to have a stop similar to stop 12. However, to limit the left hand movement of carrier *b²* a stop block 45 similar to stop 12 is necessary and as the said

two stops abut each other it would not be possible to bring the carriers *b'* and *b²* into close proximity to each other. To enable the bringing of said carriers into close proximity with each other the rear stop blocks 13 and 14 have wings 15 and 16 respectively formed thereon which have the bevelled portions 15' and 15², 16' and 16². The said wings 15 and 16 lie in the path of travel of plunger *d'* which operates the carriers *b'* and *b²*. Mounted on the front faces of said wings are stop pins 15³ and 16³ respectively against which the blocks 11 of carriers *b'* and *b²* may abut in extreme right and left hand positions. Thereby it will be noted that the separation between blocks 11 of yarn carriers *b'* and *b²* has been reduced to the width of the stop pin 15³.

50 In the present instance the stops 13 and 14 each have suitably connected thereto respectively straps 13³ and 14³ are strapped together by suitable strapping means 17 (Fig. 6) in order that the said blocks may be controlled as a unit from the stop shifting mechanism now to be described. The said 55 straps have pins 13⁴ and 14⁴ for a purpose to be hereinafter specified.

55 Mounted in front of said bar 10 on suitable supports 18 and 18' are two rods or bars 19 and 20, each bar being provided on its upper surface with a plurality of spaced holes or depressions 19' and 20', respectively, for a purpose hereinafter to be specified. A similar set of bars 21 and 22 mounted at the rear of bar 10' on supports 23 are also 60 provided.

65 The lower faces of said bars may be provided with rack teeth 19², 20², 21² and 22² respectively. Bar 19 of the front pair is adapted to be geared to bar 22 of the rear 70 pair by a gear 24 which is fixedly mounted on a shaft 25, which at its opposite end has mounted thereto a gear 24', the gear 24 meshing with the bar 19 of said front pair and the gear 24' meshing with the bar 22 of said 75 rear pair 21.

Similarly gear 26 mounted on the front end of a shaft 27 meshes with the rack on the bar 20 of the front pair and a gear 26' mounted on said same shaft 27 meshes with the 80 rack on the bar 21 of the rear pair. The said shafts 25 and 27 are rotatably journaled to a suitable mounting 28 in the frame of the machine. By this gearing arrangement motion imparted to either of the front pair of 85 bars will be transmitted to the corresponding bar of the rear pair.

90 In order to individually move each of the bars of the front pair in the present embodiment I prefer to use a ratchet mechanism for each of said bars of said pair and which is mounted near one end of the machine as for instance in the position shown in Figs. 1 and 2. The said ratchet mechanism for 95 each of said two bars comprise plates 29 and

30 respectively, rotatably mounted on a shaft 31, said shaft being suitably journaled in the frame of the machine proper. Said plates 29 and 30 are each provided with two oppositely extending wings 29' and 30' respectively in which there are arranged slots 29² in plate 29 and similar slots (not shown) in plate 30. Fixedly mounted on said shaft 31 are two laterally projecting arms 32 and 33 one for each of plates 29 and 30 and said arms are adapted to be at an angle with the wings 29' and 30'. Pivotally mounted to said arm 32 on a common pivot 32' are two pawls 32² and 32³ which extend in opposite directions. A similar pair of pawls are identically mounted on arm 33. Said pawls may engage the racks of said bars 19 and 20, pawls 32² and 32³ being for bar 19 and the other pair of pawls on arm 33 for bar 20. One pawl 33² of the latter pair is shown in Fig. 5. Each of said pawls is provided with a pin 32⁴, 32⁵ and 33⁴ and 33⁵ respectively which are adapted to lie in the respective slots 29² and the similar slots in plate 30 thereby controlling the engagement of the former with said racks 19² and 20². Suitably formed on the arms 32 and 33 are pins 32⁶, 32⁷ and 33⁶ and 33⁷ respectively, and adapted to be stretched between the said pins and the pins 30 on the pawls are coiled tension springs 34 which tend to always reduce the angle between the pawls and the arms 32 and 33. By the rotation of the plates 29 and 30 because of the engagement in the respective slots of 35 the pins on the pawls, it is possible to bring each of said pawls into or out of engagement with the respective racks of the bars 19 and 20.

In order to effect the rotation of said plates 29 and 30 suitable cam means is employed. Mounted on rotatable rods 35 and 35' respectively are two cams 36 and 37 respectively, cam 36 engaging plate 29 on the lower edge thereof and cam 37 engaging plate 30 on the lower edge thereof, so that when said cams are rotated transversely to the plane of said plates 29 and 30, they cause the latter to be correspondingly rotated on the shaft 31. In order to eliminate the necessity of two cams for each plate tension springs 36² and 37² are mounted between pins 36' and pin 29² and pin 37' and a pin (not shown) similar to pin 29² on the respective cams and plates whereby there is a tendency to always urge the rotation of said plates in one direction, and the operation of said cams is to overcome said tendency.

The rotation of the cams 36 and 37 is accomplished as follows:

Suitably mounted in the machine proper, is a shaft 38 to which are mounted sprocket drums 39 on which is mounted sprocket chain 40, and to which cam blocks 41 which control the pattern to be knitted on the machine may be removably mounted in a double row. Mul-

tiple armed levers 42 and 43 are suitably mounted for instance on shafts 44 and 45 suitably journaled in the frame of the machine. One arm 42' and 43' respectively of each said levers is so positioned as to engage with one of the rows of cam blocks 41 on said sprocket chain 40. Links 46 and 47 respectively join the arms 42² and 43² to crank arms 48 and 49 respectively, which are fixedly mounted on the cam rods 35' and 35. A spring 50 connected to arms 42² and 43² of said levers 42 and 43 continuously urges the ends of arms 42' and 43' into engagement with the cam blocks 41. Thus as the arms 42' and 43' ride over the cam blocks 41 which move with the sprocket chain 40 which is controlled by suitable means (not shown) in the machine, the said levers 42 and 43 are pivoted about their shafts 44 and 45 and by means of connecting links 46 and 47 cause the cam rods 35 and 35' and consequently cams 36 and 37 and consequently plates 29 and 30 to rotate in accordance with the displacement caused by said cam blocks 41 and consequently cause respective pawls to engage the racks 19² and 20².

Having described the means whereby it is possible to secure individual engagement of the respective pawls with the racks 19² and 20² it is necessary to describe means for causing longitudinal displacement of said pawls in order to correspondingly displace the bars 19 and 20. In order to accomplish this I provide a crank arm 51 fixedly attached to the shaft 31 at its rear end. A connecting link 52 joins said crank arm to arm 53' of a pivoted double arm lever 53 mounted for instance to the rear bar 10' of the machine. The arm 53² is provided with a longitudinal slot 53³ and in this slot one end of a sliding rod 54 is adjustably engaged as by means of bolting or the like. The said rod 54 is slidably mounted on the machine frame and is provided with adjustably positioned collars 54' only one of which is shown which are designed to engage a member (not shown) fixedly attached to the sliding carriage c, whereby when said member engages one of said collars the said rod will be shifted horizontally, consequently causing rotation of said lever 53 which in turn will cause rotation of crank arm 51 through link 52 and consequently cause displacement of the pawls which are attached to arms 32 which are fixedly mounted to shaft 31. The effective length of arm 53² is adjustable by the adjustable positioning of rod 54 in the slot 53³. Consequently, by varying the effective length of said arm 53² ultimate displacement of the pawls may be correspondingly varied as is readily seen.

The mode of operation is as follows:—

Suppose it is desired to produce work with the zigzag stripes shown in Fig. 11. In such case the yarn carriers b', b², b³, b⁴ and b⁵ each

starting from their extreme left hand positions limited by their stops must first move progressively toward the right to their extreme right hand positions and then be returned again to their extreme left hand positions. If the intermediate stops, such as 13 and 14 were rigidly held in place without any displacement whatsoever, the pattern produced would simply be a series of straight lines. However if after each complete shift of said yarn carriers from left to right the said stops themselves are shifted progressively to the left until they have been displaced a predetermined distance the first slanting portion of the zigzag of Fig. 11 will have been formed, then if the said stops are progressively shifted to the right the second zigzag portion will be formed and so on.

This operation is accomplished as follows—

Assuming that the carriage *c* is on the extreme left hand side of the machine and is beginning to move towards the right by driving means (not shown) of the machine on the rails *a'*. As it moves thusly the front plunger *d'* will ride up over the inclined edge 12' of the stop 12 and down into the cut-out portion 11' in block 11 of carrier *b'* and when it reaches the right hand end of said cut-out portion will carry the said yarn carrier along with it until said plunger is released from the block 11 when it rides over the inclined plane 15' of wing 15 on the rear stop 13, at which instant the forward end of block 11 will abut against the pin 15³ on said wing. At this same instant the plunger *d²* will have engaged the block 11 of yarn carrier *b²* and have begun to carry the said yarn carrier *b²* toward the right, and will continue to do so until released therefrom by stop 14. At the instant of release therefrom a similar plunger cooperating with the yarn carriers which are carried on the rear bar 10' will have engaged block 11 of carrier *b³* and begun to carry said carrier to the right until released by the right hand stop therefor. At the instant of release of carrier *b³*, carrier *b⁴* will be carried forward by plunger *d'* until it abuts pin 16³ on wing 16, when it will be released and then carrier *b⁵* will be seized by the rear plunger (not shown) and carried to the right to its extreme right hand stop (not shown). The stops for the yarn carrier are so arranged that the feeder of each yarn carrier will be carried up to but not across the starting point of that on the next succeeding yarn carrier.

After moving the carriers to their extreme right hand limits of their strokes, against their respective stops the carriage *c* continues to move towards the right. During this motion the cams 36 and 37 under the influence of the cam blocks 41 on the sprocket chain 40 will have been rotated so that the pawl 33³ on the plate 30 engages the rack

20² on the rod 20. Then when the rod 54 is shifted by engagement with the part of the carriage as described thereby causing the crank arm 51 to be rotated toward the right, the said bar 20 will be correspondingly displaced causing corresponding displacement to the right of the stops 13 and 14 which are attached to strapping means 17 through straps 13³ and 14³, the pins 13⁴ and 14⁴ of which engage in the perforations or depressions 20' of said bar 20. Then the carrier *c* begins to move towards the left and in so doing returns the carriers to their left hand positions against their left hand stops. The stops 13 and 14 being adapted to move as a unit and having been connected to the bar 20 of the front pair have been shifted toward the right and the stops on the rear bar 10' which have been correspondingly connected to the corresponding bar 21 of the rear pair which is geared to the displaced front bar will have also been shifted toward the right. Thereby the extreme left hand positions of carriers *b²*, *b³*, *b⁴* and *b⁵* will have been shifted slightly toward the right and correspondingly the extreme right hand position of carriers *b¹*, *b²*, *b³* and *b⁴* will have been shifted slightly to the right. Thus on the next right hand movement of carriage *c* each of the latter carriers *b¹*, *b²*, *b³* and *b⁴* will be carried slightly further to the right. This progressive shift of the stops continues as long as the cam 37 is in the position whereby the said pawl 33³ engages the said bar 20. However, as the sprocket chain 40 continues to rotate by means (not shown) in the machine in well known manner, new sets of cam blocks 41 having a different contour from the original ones will be brought into operative position at such time when the limit of the right hand shift of the said stop is desired at which time the cam 37 will again rotate to a new position releasing the right hand pawl from said bar of the pair 20 and causing the pawl 32² to engage said bar, whereupon after each left to right and right to left movement of the carriage *c* the previously shifted stops will be given a progressive movement toward the left. Thus it will be seen, by the corresponding progressive shifting of the said stops to the left and right respectively the zigzag design of Fig. 11 will be obtained. It will be noted that only one of the displaceable bars 20 of the pair 19 and 20 has been used in the operation above described and also the corresponding one 21 of pair 21 and 22. For different designs both pairs of bars may be used.

In the modification of Figs. 8, 9, and 10, means are shown whereby in a very simple manner the diamond designs shown in Fig. 12 may be knitted. In place of the stops hitherto described, I provide two bars 61 and 62 slidably mounted on the said bar 10 of the machine by means of sliding blocks 55 and 56 respectively to which opposite ends of said

bars are respectively connected. The upper edges of both said bars are adapted to lie in the path of travel of the plunger d' . Each of said bars 61 and 62 is provided with cut-in portions 61' and 62' having slanting side walls. The said two bars are adapted to be slideable relative to each other and the sliding movement of each bar is adapted to be controlled by one of the bars 19 and 20, the bar 61 for instance being connected to bar 19 and correspondingly the bar 62 being connected to bar 20. The method of connection between said bars 61 and 62 and said bars 19 and 20 respectively may be accomplished by straps 57 and 58, the strap 57 being connected to block 55 and the strap 58 being connected to block 56. Attached near the front ends of each of said straps 57 and 58 are cross arms 59 and 60 extending in the direction of said bars 19 and 20, the said arm 59 being adapted to lie over bar 19, and the said arm 60 being adapted to lie over bar 20. The said arms are provided near their ends with pins 59' and 60' which are adapted to lie in the respective perforations 19' and 20' in the said bars 19 and 20. Thus any movement of either of the bars 19 or 20 will correspondingly shift the respective bars 61 or 62.

The operation with this modification to knit the diamond design of Fig. 12 is as follows—

Initially the two bars 61 and 62 are in such position that the set-in portions in each bar are counteracted by the high portion on the other bar, so that the plunger d' moving over said bars will not be able to lower itself into the set-in portion 11' of the yarn carrier blocks 11, so that the carriers b^s and b^r will not be moved as the plunger d' sweeps across from right to left and from left to right. Then under the influence of the cam blocks 41 and the respective cams 36 and 37 the respective bars 19 and 20 are caused to shift to the right and to the left respectively, in successive steps and as this occurs the length of set-in portions between the bars 61 and 62 gradually increases and the plunger d' is able to lower itself into the set-in portions 11' of the blocks 11 and carry the said yarn carriers over an ever increasing stroke, the bevelled edges of the set-in portion on the respective bars 61 and 62 serving to actuate the plunger d' to release the same from said blocks 11 in the same manner as the bevelled portions on the stop 12 in the first modification.

After the bars 61 and 62 have been given their maximum right and left displacements, at which time the widest portion of the diamond will have been knitted, the respective bars under the influence of the cam blocks 41 and the associated mechanism are shifted from right to left and left to right respectively, progressively, to bring them to their original position relative to one another

thereby producing the second half of the diamond in the same manner as the first half has been knitted.

It will be noted that with the second modification no stop pins have been provided on the respective bars 61 and 62 and the same are not necessary if there is sufficient frictional engagement between the yarn carrier mountings and the bar 10. However, if desired such pins could be readily added.

The two patterns shown in Figs. 11 and 12 are only indicative of a plurality of varying designs and patterns which may be solidly knitted with my attachment as it will readily be seen that by varying the relative position of stops by means of the bars 19 and 20 different designs are possible.

My invention may be modified in many ways without departing from the spirit thereof and I do not wish to be limited to the details shown and described.

What I claim is—

1. In a knitting machine having yarn carriers mounted on bars, the combination with said yarn carriers, of means for controlling the strokes of said carriers, said means including stop blocks adapted to be mounted on said yarn carrier bars, the ends of said blocks being tapered, wings on said stop blocks and stop pins mounted on said wings. 90

2. In a knitting machine having yarn carriers mounted on bars, stop blocks, for the yarn carriers to limit the strokes of the latter, said stop blocks being adapted to be mounted on said yarn carrier bars, the said blocks forming stops for certain of the said carriers, wings on said stop blocks and pins mounted on said wings and forming stops for others of said yarn carriers. 100

3. In a knitting machine, the combination with the yarn carriers mounted on the carrier bars, of means for controlling the strokes of said carriers, said controlling means including stop blocks mounted on said bars, a plurality of said stop blocks being provided with wings, and abutments on said wings also adapted to serve as stops for carriers. 110

4. In a knitting machine, the combination with the movable yarn carriers of means to actuate said carriers in succession, means for controlling the stroke of each of said yarn carriers whereby each yarn carrier will come to rest at the starting position of the next succeeding yarn carrier, the movement of which then commences, and means for adjustably positioning said controlling means for formation of designs, said adjustably positioning means including slideable bars adapted to be connected to said controlling means, means for coupling said slideable bars to said controlling means and means for shifting said slideable bars, said last named means including toothed sections on said slideable bars, members adapted to engage 125

said toothed sections and means for actuating said members to cause them to engage said toothed sections.

5. In a knitting machine, having a needle bed and yarn carrier bars located on both sides of said needle bed, the combination with the yarn carriers mounted on said bars of means to actuate said carriers in succession, means on said bars for controlling the stroke of each of said yarn carriers whereby each one of the latter will come to rest at the starting position of the next succeeding yarn carrier, the movement of which then commences and means for adjustably positioning said controlling means, said adjustably positioning means including slidable members mounted at the front and rear of said carrier bars, means for coupling said front slid- 70

means for adjusting said controlling means for formation of designs, said adjusting means including slidable bars, means for coupling said slidable bars to said controlling means, and means for moving said slidable bars, said last named means including toothed sections formed on said slidable bars, means for engaging said toothed sections and means for actuating said engaging means to cause them to engage said toothed sections, said means for controlling the strokes of said yarn carriers including stop blocks slidably mounted on said machine in the path of said yarn carriers, the ends of said blocks being tapered.

12. In a knitting machine the combination with the yarn-carrier, of means for controlling the strokes of said yarn-carrier and means for adjusting said controlling means for formation of designs, said adjusting means including slidable bars, means for coupling said slidable bars to said controlling means, and means for moving said slidable bars, said last named means including toothed sections formed on said slidable bars, means for engaging said toothed sections and means for actuating said engaging means to cause them to engage said toothed sections, said means for controlling the strokes of said yarn carriers including slidable bars having recesses with tapered walls.

13. In a knitting machine the combination with the yarn-carrier, of means for controlling the strokes of said yarn-carrier and means for adjusting said controlling means for formation of designs, said adjusting means including slidable bars, means for coupling said slidable bars to said controlling means, and means for moving said slidable bars, said last named means including toothed sections formed on said slidable bars, means for engaging said toothed sections and means for actuating said engaging means to cause them to engage said toothed sections, said means for controlling the strokes of said yarn carriers including stop blocks slidably mounted on said machine in the path of said yarn carriers, said blocks having wings formed thereon and pins mounted on said wings to form stops for others of said yarn carriers.

14. In a device as per claim 7, in which said connecting means between bars on the respective sides of said needle bed comprises a rotatably borne shaft extending transversely between said bars and gears fixed to said shaft and meshing with the toothed sections of bars of the connected group.

15. In a device as per claim 8, in which said connecting means between bars on the front of and rear of said machine comprise, a rotatably borne shaft extending from front to rear of said machine, and gears fixed to said shaft and meshing with the toothed sections of bars of the connected group.

16. In a knitting machine, the combination with the movable yarn carriers, of means to

actuate said carriers in succession, means for controlling the stroke of each of said yarn carriers whereby each carrier will come to rest at the starting position of the next succeeding yarn carrier, the movement of which then commences, slidable members mounted at the front and back of said machine and adapted to be connected to said controlling means, means for coupling members in the front and back of said machine, ratchet means for engaging said slidable members and shifting the latter, and cam means for controlling said ratchet means.

17. In a knitting machine having a needle bed and yarn carriers slidably mounted on both sides of said needle bed, the combination with the yarn carriers of means to actuate said carriers, means for controlling the stroke of each of said yarn carriers and means for adjusting said controlling means for the formation of designs, said adjusting means including slidable bars mounted on both sides of said needle bed, means for coupling said slidable bars to said controlling means and means for moving said slidable bars, said last named means including connecting means between bars on the respective sides of said needle beds, ratchet means for engaging said slidable bars and means for controlling said ratchet means.

18. In a knitting machine having a needle bed and yarn carriers slidably mounted on both sides of said needle bed, the combination with the yarn carriers of means to actuate said carriers, means for controlling the stroke of each of said yarn carriers and means for adjusting said controlling means for the formation of designs, said adjusting means including a slidable bar mounted on each side of said needle bed, means for coupling said slidable bars to said controlling means and means for moving said slidable bars, said last named means including toothed sections on said slidable bars, gear coupling between said slidable bars, pawl members for engaging the toothed section of one of said bars and means for actuating said pawl members to engage said toothed sections.

In testimony whereof I affix my signature.

DIETRICK J. WERFELMAN.
